WALL MOUNTED SOUND TRANSDUCER

Benigno A. Rivera, Milaville, Puerto Rico, assignor to
Harold D. Linden and Lawrence A. Gordon, both of
San Juan, Puerto Rico

Filed Mar. 13, 1968, Ser. No. 10,965

Term of patent 14 years

Int. Cl. D14—01

U.S. Cl. D26—14

FIG. 1

FIG. 2

FIG. 3

FIG. 1 is a front perspective view of a wall mounted sound transducer;

FIG. 2 is a rear perspective view thereof; and

FIG. 3 is a side elevation thereof, the opposite undisclosed side is a mirror image thereof.

I claim:

The ornamental design for a wall mounted sound transducer or the like, as shown and described.
